CONTAINER

Filed Nov. 1, 1930

INVENTOR.

HENRY M. DILLHOEFER, JR.

By Geo. B Pitts
ATTORNEY.

UNITED STATES PATENT OFFICE

HENRY M. DILLHOEFER, JR., OF CLEVELAND HEIGHTS, OHIO, ASSIGNOR TO THE BYRNE MANUFACTURING COMPANY, OF CLEVELAND, OHIO, A CORPORATION OF OHIO

CONTAINER

Application filed November 1, 1930. Serial No. 492,790.

This invention relates to a container, more particularly to the bung and its mounting, whereby the bung is rigidly secured in the container wall, so that a closing plug or other device may be inserted and removed as often as desired without danger of loosening the bung with resulting leakage.

One object of the invention is to provide in a container an improved bung and mounting therefor in which the interlocking means are disposed between the body portion of the bung and portions of the container wall so that such means may extend over or along a major portion of the bung.

Another object of the invention is to provide in a container an improved bung and mounting therefor in which the interlocking elements are disposed intermediate the bung flange at one end and a riveted portion at the other end, the latter serving to reinforce the interlocking wall portion of the container.

Another object of the invention is to construct in a container an improved bung and mounting therefor in which interlocking elements are disposed between the side walls of both the flange and body portion of the bung and the adjacent or opposed walls of the container.

Other objects of the invention will be apparent to those skilled in the art to which my invention relates from the following description taken in connection with the accompanying drawing, wherein,

Fig. 1 is a fragmentary plan view of a container embodying my invention.

Fig. 2 is a section on the line 2—2 of Fig. 1.

Fig. 3 is a plan view of the metal after it is distended to receive a bung.

Fig. 4 is a transverse section of my improved bung before it is mounted in the wall of a container.

Fig. 5 is a bottom plan view of the bung before it is mounted in the wall of the container.

Fig. 6 is a fragmentary section showing the container wall shaped to receive a bung.

Fig. 7 is a fragmentary section showing a slightly modified form of construction.

Fig. 8 is a side elevation of a bung of the form shown in Fig. 7.

Fig. 9 is a fragmentary section of a container wall shaped to receive a bung of the form shown in Fig. 8.

Fig. 10 is a fragmentary plan view of a container showing another embodiment of my invention.

Fig. 11 is a fragmentary section of the container wall, of the embodiment shown in Fig. 10.

My invention is applied to a sheet metal wall of a container. The container shown comprises a sheet metal body portion 1 and a sheet metal head 2, suitably connected as by a double seam 3.

The bung, which is indicated as an entirety at 4, is preferably mounted in the head 2, and is threaded interiorly to receive a closing plug (not shown). The head 2 is formed with an opening and then the walls surrounding the opening are distended in one direction to form below the container wall (a) a pocket or annular chamber 5 having depending side walls 5a and a bottom wall 5b and (b) a neck 6 depending from the inner circumferential edge of the bottom 5b.

The walls of the neck are formed of flat integrally connected sections 6a disposed at angles one to another, there preferably being eight flat sections.

The bung 4 comprises a body portion 4a terminating at its lower end in a relatively thin wall 7, which is riveted over the free or lower edge of the neck 6, as shown in Fig. 2, and a flange 4b at its upper end, which flange fits into the pocket or chamber 5, being held therein by the riveted over wall 7. As shown, the riveted over wall 7 and flange 4b co-operate to hold the body portion in the neck and against endwise movement therein. The exterior wall of the body portion 4a between the wall 7 and flange 4b is provided with flat sides 8 (see Fig. 5) corresponding in size and number to those provided in the neck 6, so that the body portion snugly or tightly fits into the latter, the angularly arranged opposed sides serving as an interlock between the bung and neck to prevent the former from turning. It will thus be seen that the opposed walls 6a, 8, serve to prevent turning of the bung and that the flange

4b and wall 7 serve to maintain the bung in its seat or against endwise movement.

In Figs. 7, 8 and 9, I have shown a slightly different embodiment of the invention in which the flat sides of the bung body and flat sides of neck are inclined or tapered as shown at 8', 6a', respectively, which form of construction facilitates the making of the bung and shaping of the neck, as well as the assembly of the bung in position in the latter.

It will also be noted that the riveted over wall 7 also interlocks with the interior and exterior faces of the angular sides 6a, 6a', at or adjacent their lower free ends and operates with such ends to supplement the interlocking between such sides and the opposed sides of the bung.

In Figs. 10 and 11 I show a further embodiment of the invention in which the side wall 20 of the chamber 5, instead of being circular, is of polygonal shape having contiguous flat sides 5' and the flange of the bung is similarly shaped to provide flat sides 4b' which interlock with the sides 5'.

25 In this latter form of construction, it will be noted that all side portions of the bung from end to end thereof are interlocked with the container wall and in addition thereto the depending wall 7' at the lower end of 30 the bung being riveted over the flat sides 6a' of the neck results in providing a supplemental interlock with the depending neck.

To those skilled in the art to which my invention relates many changes in construction 35 and widely differing embodiments and applications of the invention will suggest themselves without departing from the spirit and scope of the invention. My disclosures and the description herein are purely illustrative and are not intended to be in any sense 40 limiting.

What I claim is:

1. A container having a sheet metal wall formed with an opening, the wall surrounding 45 said opening being distended to form a chamber having side and bottom walls and a neck depending from the inner circumferential edge of said bottom wall and said neck consisting of contiguous flat side walls disposed at angles one to another, and a bung comprising a body portion having exterior flat side walls fitting into and having interlocking relation with said neck and a flange at its upper end fitting into said chamber, the 50 lower end of said body portion terminating in a continuous wall which is riveted over the lower free edge of said neck and cooperates with said flange to position the bung in said neck and chamber.

60 2. A container having a sheet metal wall formed with an opening, the wall surrounding said opening being distended to form a chamber neck extending vertically from the circumferential edge of said opening, and 65 said neck consisting of contiguous flat side

walls disposed at angles one to another and tapering inwardly toward its free end, and a bung comprising a body portion having exterior flat tapered side walls fitting and having interlocking relation with the side walls of said neck and the lower end of said body portion terminating in a continuous wall which is riveted over the lower free edge of said neck and co-operates with the tapered walls of said body portion to position the bung in said neck.

In testimony whereof, I have hereunto subscribed my name.

HENRY M. DILLHOEFER, JR.
